UNITED STATES PATENT OFFICE.

WILLIAM NOBLE, OF NORTHAMPTON, MASSACHUSETTS, ASSIGNOR, BY MESNE ASSIGNMENTS, TO PRO-PHY-LAC-TIC BRUSH COMPANY, OF NORTHAMPTON, MASSACHUSETTS, A CORPORATION OF MASSACHUSETTS.

DRILLING MACHINE.

Application filed May 18, 1923. Serial No. 639,990.

My present invention has for its object to provide a machine for drilling holes in articles such, for instance, as the handles of celluloid or bone tooth brushes. The machine embodying my invention, in the particular form in which I have put it into actual practice, is intended to drill the holes in the handles of celluloid tooth brush blanks. As will be understood by those skilled in the art, these handles are formed by being molded in dies under pressure, and the hole in the end of the handle by which the completed tooth brush may be hung up is partly formed by the dies, but a web is left, closing the hole. This web must be removed by a drilling operation. The particular object of the invention is to provide a drill to perform this operation at high speed and in an accurate and economical manner.

The invention will be fully understood from the following description when taken in connection with the accompanying drawings, and the novel features thereof will be pointed out and clearly defined in the claims at the close of this specification. In said drawings:—

Fig. 1 is a plan view and Fig. 2 a section of a tooth brush blank to be drilled on the machine embodying my invention.

Fig. 3 is a side elevation of the machine.

Fig. 4 is a top plan view of the machine embodying my invention.

Fig. 5 is a section taken on line 5—5 of Figure 4.

Referring now to the drawings, and particularly to Figs. 1 and 2, there is shown a tooth brush blank A in the condition in which it is when it comes from the molding dies. At the end of the handle portion is a hole B which is closed by a web b, the object of the machine being to remove this web.

Referring to Figs. 3 and 4, the machine is provided with a frame C having a pedestal 11 on which is mounted a table 12 which rotates intermittently about a hub 13 rising from the top of the pedestal. The top of the table is provided with a series of raised spacing members 14 between each adjacent pair of which there is a space of the size and shape necessary to receive a tooth brush handle. These handles, designated A, are set in between the spacing member at the front of the machine with their inner ends abutting against a stationary cam 15 secured to the

hub 13 of the pedestal. There is also secured to the pedestal a stationary guide flange 16 which co-operates with the cam 15 to cause the blanks to be fed into proper position. This guide flange, as viewed in Fig. 4, is provided with a flaring end as indicated at 17, but is concentric with the axis of rotation of the table in the rearward left-hand quadrant, this being the quadrant in which the drilling takes place. The cam 15, when viewed in Fig. 4, is also concentric with the axis of rotation of the table in the rearward left-hand quadrant and ends in the first part of the rearward right-hand quadrant, this being the quadrant in which the ejection takes place. The guide flange also terminates in the first part of the latter quadrant. The radial distance between the guide flange 16 and the cam 15 in the rearward left-hand quadrant is approximately equal to the length of a tooth brush blank. In the two forward quadrants, the cam 15 is cut away, as shown at c, these being the quadrants in which the undrilled brush blanks are put in place by the operator. From the foregoing it will be seen that the operator places a brush blank in each of the spaces between the two adjacent partitions 14 without taking care to position the blanks radially. As the table rotates, the cam 15 gradually pushes in an outward radial direction any blanks which come in contact therewith, while any blanks which come in contact with the flaring end 17 of the guide flange are pushed inwardly in a radial direction. This occurs just as the blanks arrive at the beginning of the rearward left-hand quadrant, as viewed in Fig. 4. Thereafter, they are held properly positioned between the concentric edge of the cam 15 and the concentric edge of the guide flange 16 until they have passed the drills, have been drilled and are ready to be ejected from the machine. The ejection apparatus will be described hereinafter.

In the drawings I have shown two drills which operate simultaneously on alternate brush handles, the drills being spaced some distance apart, as viewed in Fig. 4, to provide space for the operating mechanism. In practice, the drill 19 bores the handle which is just passing from the rearward left-hand quadrant into the rearward right-hand quadrant, while the drill 18 bores an alternate blank seven spaces to the left. It will also

be understood that after each pair of holes is drilled, the table is rotated through an angular space equal to the angular space occupied by the number of brush backs which are drilled simultaneously. It is also to be understood that I do not limit myself to a machine which drills two brush backs simultaneously since additional drill spindles can be provided, in which case the table will be caused to move through an angular space equal to the angular space occupied by the blanks which are drilled simultaneously. Inasmuch as in drilling work of this character, it is structurally impossible to engage adjacent blanks, the drills should be positioned so that no blank will be brought under a drill a second time. This is accomplished in the construction illustrated by providing a number of blank positions between the drills which is a multiple of the number of drills employed.

The main driving shaft of the machine is shown at 20, being driven by a belt 21 running on a pulley 22. On the main driving shaft 20 are two pulleys 23 which drive pulleys 24 on the drill spindles 25 by means of two quarter-turn belts 26 and 27. The drill spindles are carried in brackets 28 and normally are held out of contact with the work by springs 29 acting on collars 30.

The main drive shaft 20 also carries a sprocket wheel 31 over which runs a chain 32 which drives another sprocket wheel 33 fast to a shaft 34. The shaft 34 is provided with a worm 35 which meshes with a worm gear 36 on a vertical cam shaft 37. This cam shaft carries four cams, to wit, the ratchet cam 38, the stop cam 39, the drill cam 40, and the ejector cam 41. The ratchet cam 38 actuates an arm 42 pivoted at 43 to the frame of the machine. This arm swings in a horizontal plane and is located under the table. At the inner end of this arm is bolted, as shown at 44, a second arm 45 which carries a pawl 46 held by means of a spring 48 against teeth 47 formed in a ratchet wheel 10 rigidly secured to the table 12. The position of the second arm 45 relative to the arm 42 can be adjusted by the bolt 44, and in this way the table can be positioned accurately with regard to the drill spindles at the end of each movement. As previously stated, the angular space through which the table must be rotated after each operation is determined by the number of blanks which are drilled simultaneously and therefore the angular space between the adjacent teeth 47 will be determined in the same way.

As it is essential that the table should be brought to a stop after each forward movement in exactly the right position and should not be permitted to overrun, I provide a stop finger 49 adapted to enter the holes 50 in the space between successive teeth. The finger 49 is formed on the end of a lever 51 pivoted

at 52 and is operated by the stop cam 39. This cam is so constructed that the finger will be withdrawn just before the forward feeding movement takes place, thereby releasing the table, and will be inserted in the next hole, accurately positioning the table just before the drills contact with the handles.

The drill spindles are moved vertically against the springs 29 by means of a Y-shaped lever 53 pivoted at 54 and having two arms *e* and *f* which contact with the tops of the drill spindles. The tail of the Y-shaped lever 53 is engaged by a vertical plunger 55 slidable in guides 56 on the bracket 28 which forms a part of the frame of the machine. The lower end of the rod 55 carries a roll 57 which rests on the drill cam 40, already referred to. It will be seen that as the cam 40 revolves, it will raise the member 55, swinging the Y lever 53 about its pivot 54 and depressing the two drill spindles simultaneously against the pressure of the springs 29. It will also be seen that the springs 29 restore the parts to their former position as the cam roll 57 rides off the cam 40.

During the drilling operation it is essential that the blanks be held firmly to prevent displacement. Accordingly, the cam member 15 and the guide member 16 are provided with projecting portions *d* and *a* respectively, said projections being in radial alignment with the drills and extending out over the path of the blanks, as shown in Fig. 5. When the blank comes into position to be drilled, its ends are underneath these projections and it is therefore prevented from tipping up and being displaced.

At 60 is shown a cam roll engaging the ejector cam 41. This cam roll 60 is mounted on one end of a slide rod 61 carried in guides 62 in a portion of the frame of the machine. The outer end of the slide rod 61 is loosely connected to the ejector lever 63 pivoted at 64 to the frame of the machine. The cam roll 60 carried by the slide rod 61 is held in contact with the cam by means of a spring 65 acting on the ejector lever 63. The ejector lever 63 carries on the end toward the table a downwardly extending finger 66 which, in normal position, is located adjacent the inner end of the handles. It will therefore be seen that each swinging movement of the ejector lever will knock the handles which are between it and the rim outward along a radial line so that they will fall into a spout 67 by means of which they are conveyed away from the machine.

What I claim is—

1. In a machine of the character described, a revolving table, partitions forming radially-arranged positions for the articles to be operated upon, a stationary cam member the periphery of which is adjacent the inner ends of said positions, said cam member having a portion which is concentric with the axis of

rotation of the said table, and another portion which is non-concentric therewith, the remainder of the cam being cut away.

2. In a machine of the character described, a revolving table, a stationary rim adjacent the edge of the table, one end of the rim being flared away from the table, a stationary cam member the periphery of which is adjacent the inner ends of the positions on the table, said cam member having a portion which is concentric with the axis of rotation of the table and with said rim, and another portion which is non-concentric and flares away from the flaring portion of the said rim.

3. In a machine of the character described, a revolving table, partitions thereon forming radially arranged positions for the articles to be operated upon, a plurality of drill spindles, pawl-operated means for giving the table a step-by-step motion, a cam to actuate said means, common means for actuating said drill

spindles, a cam therefor, said cams being arranged to operate alternately, and stationary cam means for radially positioning the articles between said partitions. 25

4. In a machine of the character described, a revolving table, partitions thereon forming radially arranged positions for the blanks to be operated upon, a plurality of drill spindles 30 similarly positioned with respect to said blank positions and each spaced to provide a number of blank positions therebetween which is a multiple of the number of drills employed, means for operating the same, and means for intermittently rotating the table through an angular space equivalent to the angular space occupied by the number of blank positions equal to the number of drills employed thereby bringing each of said positions opposite one of the drill spindles. 35

In testimony whereof I affix my signature.

WILLIAM NOBLE.
